UNITED STATES PATENT OFFICE.

HENRY E. HARRIS, OF PORTLAND, OREGON.

COOLING BOX.

Application filed March 30, 1925. Serial No. 19,398.

My invention relates to improvements in a cooling box, for use in conjunction with a brine unit type refrigerating machine, wherein it is desirable to maintain within 5 the cooling box different temperatures for different purposes and consists primarily of a lidded structure having disposed therein various compartments and means for regulating the temperature in the different compartments.

A further object of my invention consists in a compartment structure surrounded with insulating material and having circulating therein a cooling medium, and having disposed within certain compartments surrounded by the cooling circulating medium means for controlling the temperatures to be developed or maintained within the compartments by regulating automatically, the 20 volume of the cooling medium to be circulated therearound.

A further object of my invention is to automatically regulate, by a temperature thermostatic control, through the medium of 25 a three way valve, the volume of cooling circulating medium passing around the compartments to be cooled and therefore control the temperature, of the compartments, within certain ranges of temperature, without 30 changing the temperature of the circulating cooling medium.

A further object of my invention, is to control the temperature of certain of the compartments, within the box, within certain 35 and limited ranges of temperature; due to the distance of the compartments from the automatic regulating control device.

A further object of my invention consists in causing the circulating cooling operating medium, as brine, to follow a circuitous path in and around certain of the compartments whose temperature is to be regulated and in so doing, to create and maintain different temperatures, in the different compartments, 45 along the channel of the cooling circulating operating medium.

A further object of my invention consists of forming a box of low heat conductivity, the placing of a vat therein of a number of 50 different compartments, of placing a layer of substantial thickness of insulating materials between the inner walls of the box and the outer walls of the vat, and the placing within the vat of a number of different 55 compartments adapted to the circulating therearound of a cooling circulating me-

dium, as brine, and a closed circuit of piping adapted to circulate the cooling medium from the refrigerating machine through the box and back to the refrigerating machine, and automatic means within the circuit 60 regulating the channel of flow of the cooling medium, and lidded openings to each compartment within the box.

With these and incidental objects in view, 65 the invention consists in certain novel features of construction and combination of parts, the essential elements of which are set forth in the appended claims and to a preferred form of embodiment of which is 70 hereinafter shown with reference to the drawings which accompany and form a part of this specification.

In the drawings,—

Fig. 1 is a plan view of my new and improved cooling box.

Fig. 2 is a front side elevation, partially in section, of the mechanism shown in Fig. 1.

Fig. 3 is an enlarged sectional view taken 80 on line 3—3 of Fig. 2, looking in the direction indicated.

Fig. 4 is an enlarged, sectional, plan view of the mechanism shown in Fig. 2, taken on line 4—4 of Fig. 2, looking in the direction 85 indicated.

Fig. 5 is a cross section view taken on line 5—5 of Fig. 4, looking in the direction indicated.

Like reference characters refer to like 90 parts throughout the several views.

1 is the main box structure made of low heat conducting material, as wood, having an inner vat compartment 2 disposed therein and between the two a heavy and substantial coating of insulated material, 2^a, as cork, or other suitable material to maintain 95 therein the low temperatures thus created.

A cooling circulating medium, as brine, is circulated through the inlet pipe 3, by a circulating pump located upon the refrigerating machine not here shown and which is permitted to enter the chamber 4, through the pipe and around the cooling compartment 5, located therein which is maintained 100

by the wall structure 6 of the same. It is intended by my construction that the lowest temperatures to be maintained within this cooling box will be maintained within the compartment 5, and, therefore, the cooling 110 circulating medium, as brine, shall be taken directly from the liquid surrounding the ex-

pansion chamber of the refrigerating device and deposited therearound. A baffle plate 8 disposed within the space 4, will cause a circulation of the medium around the side 5 walls and bottom walls of this compartment and the same will leave the compartment through the pipe 9; disposed within this pipe is a three way valve 10, having a valve arm 11, disposed thereon and attached to 10 the valve stem of the valve to which a heat regulating thermostat piston 12 is attached, the thermostat 13, is disposed within the wall structure of the compartment and which is adapted to being set at the temperatures required to be maintained within 15 a compartment of the device. The temperature of the thermostat is determined by the temperature of the cooling circulating medium within the space 15. An inlet pipe 20 15^a passes through the wall of the compartment and permits the cooling medium to surround the thermostat. An inlet pipe 14, leads from the three way valve and, therefore, from the circulating pipe 9, and dis- 25 charges the cooling circulating medium, within the space 15. The baffle 16, causes the cooling circulating medium to surround the compartment 17, and thence in the direction of the arrow to the tank 18, caused 30 by the baffle 19 located therein, thence around the compartment 20, in the direction indicated, created by the baffle 21, and thence around the compartment 22, caused by baffle 23, and thence around the compartment 24, caused by the baffle 25, and thence 35 back into the outlet pipe 26, through the outlet connection 27, through the wall of the cooling box. It will thus be apparent so long as the circulation is kept up and 40 some heat escapes that the compartment 17, will be somewhat colder than compartment 18, and compartment 18 somewhat colder than compartment 20, and that compartment 20 will likewise be somewhat colder than compartment 24, because of the leakages of 45 the temperature in the cooling medium, as the same passes from compartment to compartment. If the thermostat 13, is set for a certain temperature to be maintained with- 50 in the cooling circulating medium in and around the first compartment 17, when this temperature is reached, the thermostat will be operated and the valve stem 11, will shut off the inlet three way valve and the cooling 55 circulating medium will pass directly for its outlet through pipe 9, and pipe 26, back to the expanding tank surrounding the expanding chamber of the refrigerating machine; but when the temperature rises above 60 that required, the valve will be opened and a certain amount of the cooling circulating medium will pass in and around the compartments, as described. It will thus be apparent to those skilled in refrigerating mat- 65 ters that I have created a device adapted to

automatically regulate the temperatures to be maintained therein within certain temperature limits.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is,—

1. A cooling box comprising an insulated frame structure, vats disposed therein, one of said vats having a plurality of compartments therein, vertical baffle partitions connecting the walls of alternate compartments with the walls of the vat to form a circuitous channel for the circulation of a cooling and refrigerating medium between and around said compartments, and a piping system to carry the cooling and refrigerating medium to and from said vats. 80

2. A cooling box comprising a frame structure having a plurality of chambers, vats within the chambers, insulating material disposed between the walls of the vats and the walls of the frame structure, a plurality of compartments disposed within one of said vats, vertical baffle partitions connecting the walls of alternate compartments with the walls of the vat to form a circuitous channel for the circulation of a cooling and refrigerating medium between and around said compartments, and a piping system to carry the cooling and refrigerating medium to and from said vats. 90

3. A cooling box comprising a frame structure having a plurality of chambers, vats within the chambers, insulating material disposed between the walls of the vats and the walls of the frame structure, a plurality of compartments disposed within one of said vats, vertical baffle partitions connecting the walls of alternate compartments with the walls of the vat to form a circuitous channel for the circulation of a cooling and refrigerating medium between and around said compartments, a piping system to carry the cooling and refrigerating medium to and from said vats, and means to maintain a required temperature in certain vats comprising a three way valve disposed along the pipe system, and automatic means to manipulate the three way valve to change the direction of flow of the circulating cooling medium, to be circulated through certain vats. 100

4. A cooling box, comprising a frame structure having a plurality of chambers, vats within said chambers, insulating material disposed between the walls of the vats and the walls of the frame structure; one of said vats having a plurality of compart- 115 120 125 130

ments disposed therein, a circuituous channel formed in said last named vat, for the circulation of a cooling medium therein, said channel being formed by connecting the 5 walls of alternate compartments to the walls of the vats by vertical baffle partitions, and a piping system to carry the cooling and refrigerating medium to and from said vats.

10 5. A cooling box, comprising an insulated frame structure having a plurality of chambers therein, vats disposed within said chambers, one of said vats having a plurality of compartments disposed therein, a circuituous

channel formed for the circulation of a cool- 15 ing medium about the last mentioned compartments by connecting the walls of alternate compartments to the walls of the vats by vertical baffle partitions; a piping system to carry the cooling and refrigerating medium 20 to and from said vats, and means to maintain a required temperature in certain vats, comprising a three way valve disposed along the piping system; and automatic means to manipulate the three way valve to change the 25 direction of flow of the circulating medium to be circulated through certain vats.

HENRY E. HARRIS.
